UNITED STATES PATENT OFFICE.

MALCOLM L. COSSITT, OF OAKLAND, CALIFORNIA, ASSIGNOR TO MANIFOLD IMPRESSIONS CORPORATION, OF CARSON CITY, NEVADA, A CORPORATION OF NEVADA.

MANIFOLDING ATTACHMENT FOR TYPEWRITERS.

Application filed October 3, 1923. Serial No. 666,289.

To all whom it may concern:

Be it known that I, MALCOLM L. COSSITT, a citizen of the United States, residing at Oakland, in the county of Alameda and State of California, have invented certain new and useful Improvements in Manifolding Attachments for Typewriters, of which the following is a specification.

My invention relates to that class of manifolding attachments for typewriters in which there is associated with the main paper guide apron on the platen carriage of the machine adapted to direct a record sheet to the line of type impact, a second apron member or a plurality thereof in spaced relation to the main apron and adapted to direct additional record sheets to said line, said second apron member or members being in the form of containers to house manifolding members, such as carbon sheets, and to present an exposed section of said sheets between the record sheets in the line of type impact. This form of attachment is disclosed in my previous Patent No. 1,433,183 dated Oct. 24, 1922; and my present invention is an improvement in this type, the improvement consisting essentially in providing for the independent movement of the containers to carry primarily the exposed section of the manifolding sheets into and out of functional position in the line of type impact, and secondarily to vary said exposed section with relation to the said line, while said section is in functional position.

Referring to the accompanying drawings—

Fig. 1 is a front elevation broken in part, of my manifolding attachment.

Fig. 2 is a cross section, on the lines 2—2 of Figs. 1 and 3, showing the means for effecting the crosswise oscillation of the functioning sections of the manifolding sheets.

Fig. 3 is a plan view of the ratchet and bar members of Fig. 2.

Fig. 4 is a detail, broken, showing the mounting upon the journal bearings of the platen shaft, of the end members or sectors of the manifolding-sheet containers, for both rotary and linear movement.

Fig. 5 is a perspective view, broken, showing the end members or sectors of one of the manifolding-sheet containers and the crank bar connected therewith and comprised in

the means for oscillating the functioning section of the manifolding-sheet both crosswise and lengthwise.

Fig. 6 is a plan view of my attachment.

Fig. 7 is a longitudinal section, broken, through one of the sheaths 11 showing the mounting of the manifolding-sheet-container therein for sliding linear movement.

Fig. 8 is an end view of a diagrammatic character, showing the platen, one sheath and one container therein, mounted for movement crosswise of the platen.

Fig. 9 is a detail in plan, similar to the plan view of Fig. 3, showing the crosswise oscillating members at a different point in their closed path.

Fig. 10 is a section of the same on the line 10—10 of Fig. 9.

Fig. 11 is a detail view showing the relation to the platen of the record paper sheets, the manifolding sheets, and the containers for the latter.

Fig. 12 is a section of the upper folded end of one of the containers showing in dotted lines the fan-folded store of the manifolding sheet housed therein.

Fig. 13 is an end view of my attachment, looking from the line 13—13 of Fig. 6, and showing the means for effecting the lengthwise oscillation of the functioning section of the manifolding sheets.

Fig. 14 is a detail showing the removable attachment of the sheath to the end plates 10 of the main apron.

Fig. 15 is a plan view of the ratchet and lever members for effecting the lengthwise oscillation of the functioning sections of the manifolding sheets.

Fig. 16 is a detail of the one-way rotatable actuating ratchet of said lengthwise oscillating means.

Fig. 17 is a detail section showing the engagement of the actuating lever 30 of Fig. 15, with the outermost bar 17 of one of the containers.

Fig. 18 is a diagrammatic view of a portion of the functioning section of the manifolding member showing by the dotted line and the circles the type impressions along the line of type impact.

Fig. 19 is a view similar to Fig. 18 to show the effect of the oscillation of the functioning section of the manifolding member

both lengthwise and crosswise in presenting fresh surfaces for the type impressions.

Fig. 20 is a plan view of my attachment with the platen removed.

5 Fig. 21 is a side elevation of one of the end sectors belonging to the outer containers, showing its skeleton character, in order to permit said ends to circle about each other and about the innermost container.

10 Fig. 22 is a detail showing the relationship of the three bars 17 and their latch pins 17'.

Referring to Fig. 1, the numeral 1 indicates the end pieces of the platen-carriage, 15 in which is rotatably mounted the shaft 2' of the platen 2. 3 is a portion of the main inking ribbon of the machine. 4 is a rod extending between and carried by the ends 1 of the platen carriage parallel with the 20 platen and lying below the line of type impact, said rod being the member upon which the spring controlled paper feed-rolls 4' are pivotally mounted. 5 is the rocking rod adapted to move said rolls to and from the 25 platen. The rods 4 and 5 together with the bracket 6 and its foot roller 7, Figs. 2 and 10, are herein shown merely to indicate convenient parts found in a well known type of machine, and serving as a mount for certain operative mechanisms to be carried by the platen carriage, and comprised in my 30 attachment, as will be hereinafter described. 8 is a fixed rail carried on the frame of the machine, a portion of which is indicated at 35 8' and upon this rail the foot roller 7 travels back and forth with the platen carriage, Figs. 2, 10 and 13. For the purposes of my invention this rail 8 indicates any part of the machine frame fixed with relation to the 40 platen carriage movement and serves as a means for carrying other mechanisms of my attachment to be presently described. 9, Figs. 6 and 13, is the main paper guide apron carried by the ends 1 of the platen carriage. This apron is in general like the 45 ordinary apron of typewriters. It extends from an elevated line back of and properly spaced from the platen, downwardly towards and under the platen for the usual 50 portion of the lower arc thereof as seen in Fig. 13. It is to be noted, however, that, for purpose hereinafter described, the main apron 9 is made in sections hinged together at 9', Fig. 13, whereby the lower section 55 may be turned back when necessary. Secured to the inner face of the apron 9 as seen in Fig. 6 are plates 10 one near each end. Carried by and between the plates 10 are the U-shaped sheaths 11, one or more in 60 number, three being here shown. These sheaths are disposed with their closed bights uppermost and their open ends downward as shown in Fig. 8; and with respect to each other and to the main apron they are relatively widely spaced above and thence con-

verge downwardly towards the platen as seen by the dotted lines in Fig. 13. The sheaths 11 thus form initial supplementary paper guide aprons for a plurality of record sheets introduced between them. Said 70 sheaths are removably mounted on the plates 10, being fitted between guide flanges 10' and held by spring latch pins 10'', Figs. 1 and 14. 12 are containers for the manifolding members. The containers are best made 75 of springy sheet metal folded centrally to a double thickness as seen in Fig. 8, the folded end fitting snugly but slidably in the sheaths 11. Emerging from the open end of the sheaths the containers with their 80 double walls pressing relatively closely, Fig. 8, pass down under the platen, between it and the main apron 9 as in Fig. 13, and extend beyond said main apron and up in front of the platen as seen in Figs. 1, 6, 8 85 and 13, thus forming in conjunction with their sheaths guide aprons for other record sheets. Each container at each end of its front edge is formed with arms 13 under which the paper feed-rolls 4' play as seen in 90 Fig. 1; and between these arms the front edge of the container is depressed as seen at 12' in Fig. 1 below the line of type impact. The end arms 13 connect each container with 95 corresponding end members or sectors 14, the hubs 14' of which are rotatably and linearly slidably mounted upon the journal bearing 2'' of the platen shaft 2', as seen in Fig. 4, and are provided with hand levers 15 for operating them, Figs. 1, 5, 6 and 13. The manifolding members indicated by 16, Figs. 1, 11 and 12 are best in the form of 100 carbon paper each being initially a web of any desired length, the intention being to use a web adapted to be drawn upon for use during a relatively long period of time. The carbon paper is stored in proper form, say, for example, fan-folded, as indicated in Fig. 12 in the folded upper portion of 105 the containers 12, which portions are slidably housed in the sheaths 11. The end of each strip of carbon paper is drawn out between the relatively close pressed walls of the container, see Fig. 12, until a ribbon-like section is exposed in the line of type impact as seen in Fig. 1 above the depressed 110 front edge 12' of said container.

The operation of the attachment as far as described is as follows:

The containers 12 being loaded with their supply of carbon paper 16 as in Fig. 12 and fitted in their sheaths 11, and about the platen, all said containers are by means of the hand levers 15 partially withdrawn to 120 a position to carry their exposed section of carbon paper out of use, that is to say, the containers slide upwardly in their sheaths, their front edges with their protecting exposed carbon paper sections being thereby 125 lowered below the line of type impact. In 130

this position the typewriter may be used to make only the single record in the usual manner, no duplicate being desired.

If now one duplicate be wanted a second record sheet is introduced upon the upper surface of the sheath 11 nearest the main apron 9, the first record sheet being introduced upon the main apron, and both sheets are fed forward by the platen to the line 10 of type impact. They are however separated by the intervening container 12 and then this container, by the operation of the appropriate hand lever 15 is moved forward to carry its exposed section of carbon paper 15 into registry with the line of type impact, said section lying between the two record sheets. If a second carbon is wanted the above described adjustment of the next container is made in like manner, and so too 20 with the third container when a third carbon is desired. The relation of the several record sheets indicated in dotted lines by 50, and the carbon sheets 16 are clearly seen in Fig. 11. When that ribbon-like section 25 of the carbon paper 16 exposed to the impact of the type, is exhausted, it is drawn forward from the open end of the container and torn off, and by this operation a fresh ribbon-like section of carbon paper 30 is exposed for use; and this may be continued until the supply of carbon paper stored in the container is used up.

To reload the containers, they are removed from their sheaths, an operation permitted 35 by the hinged section of the main apron 9. Fresh carbon paper supplies are then placed in the containers by merely spreading them open sufficiently and then all the parts are assembled once more. The containers 12, 40 in order to render them sufficiently flexible may be slotted as shown in Fig. 20 at 51. In the practical operation of manifolding devices wherein the manifolding impression member is presented in the form of a ribbon-like section of a sheet or strip, successive sections of which are drawn out for use, it is necessary, in order to give the section a maximum life of usefulness, that it be presented in such manner as to receive 50 the impact of the type over its entire surface. This is accomplished by repeated limited adjustments of the section with relation to the line of type impact, in some cases the adjustment being an oscillation cross- 55 wise of said line, in other cases, lengthwise thereof and in still others both crosswise and lengthwise, the latter being the most complete, in that it takes care both of the width of the section and of the intervals 60 lengthwise between the points of impact. This is shown in Figs. 18 and 19. Furthermore, in some cases, this adjustment or oscillation is dependent upon and effected at the time of the line spacing movement of 65 the platen, and in other cases it is effected

by the reciprocal travel of the platen carriage.

In the full development of my present manifolding attachment, I provide means for shifting the containers 12 to reciprocate 70 the exposed ribbon-like sections of their carbon papers both crosswise of the line of type impact and lengthwise thereof, and although in the broadest aspect of my invention these means may be dependent either 75 upon the line-spacing movement of the platen or upon the reciprocal travel of the platen carriage, I prefer a construction utilizing the carriage travel. This will now be explained. Secured to and extending between the corresponding end sectors 14 of each container 12 is a crank-bar 17, best seen in Fig. 5.

Secured to some portion of the fixed frame of the machine, here shown as the rail 8, is 85 a standard 18, Figs. 2 and 10, in the head of which is journaled a ratchet 19 carrying an eccentrically located stud 20 against which the edges of the crank bars 17 are adapted to bear when the containers have 90 been initially moved, as heretofore described, in order to place their ribbon-like sections of carbon paper in functional position in the line of type impact. Springs 21, Fig. 13, applied to the hand levers 15 serve to 95 hold said bars 17 to said stud; while yieldable latches 21' as in Fig. 13 coacting with pins 17' on the ends of bars 17 counteract said springs to hold the bars away from the eccentric pin 20, when the containers are 100 drawn back out of use. Upon the bracket 6 carried by the rod 4 of the platen carriage is secured a spring pawl 22 adapted to engage the ratchet 19 in one direction and to slip it in the other direction, Figs. 105 2, 3, 9 and 10. It will now be seen that when, during the travel of the platen carriage, the spring pawl 22 engages the ratchet 19, it will turn said ratchet one tooth and the eccentrically located stud 20 of said 110 ratchet bearing against the crank bars 17 will correspondingly slightly move the containers 12 to carry their ribbon-like sections of carbon paper crosswise of the line of type impact; and, on account of the eccentric closed path of the stud 20, and the fact that the crank bars 17 are held against it, this crosswise adjustment will be an ultimately 115 reciprocal, or back and forth adjustment of the exposed sections of the manifolding members across the line of type impact, thereby utilizing the entire width of the said sections. It will be noted that as the crank bars 17 contact with the stud on one side 120 only and only when the containers are in functional position, the main adjustment of said containers to carry them into and out of functional position is not interfered with, as the crank bars may be withdrawn backwardly away from the stud altogether and 125 130

held back by the latches 21'. It will also be noted that any one or more of the crank bars may be moved down to coat with said stud, according to the number of carbon copies desired.

To provide for the lengthwise oscillation of the manifolding member containers, there is the following mechanism.

It will be seen by reference to Fig. 4 that the hubs 14' of the end sectors 14 of the containers 12 are so mounted upon the journal bearings 2'' of the platen shaft 2' as to be capable not only of rotary movement, but of a linear movement as well, sufficient play 15 on said bearings being provided. It follows that if said sectors be moved linearly, the containers 12 will adjust their exposed sections of carbon paper lengthwise of the line of type impact. It will also be seen that as 20 the crank bar 17 of the outermost container is the first to be moved into functional position, a longitudinal movement imparted to said bar will not only adjust its own container, but will also adjust the other containers, due to the grouping of the hubs 14' of the sectors 14 of said containers upon 25 the platen-shaft bearings 2''. Therefore, whether one or more carbon sections are being used, the longitudinal movement of 30 the outermost crank-bar will effect the required linear adjustment.

Referring now to Figs. 13, 15, 16 and 17, there is secured upon the bracket 6 carried by the rod 4 of the platen carriage a bracket 35 23, upon which is rotatably mounted an annular ratchet 24 which at a given point in the travel of the platen carriage is adapted to contact with and to be rotated by a fixed stop member 25 on the frame of the machine. 40 Lying within the annular ratchet as in Figs. 15 and 16 and independently rotatable is a disk 26, the periphery of which has a series of cams 27 so related to the inner circle of the ratchet, that in conjunction 45 with intervening rolling members 28, the rotation of the ratchet in one direction will clutch the cam disk 26 and turn it, while the rotation of the ratchet in the other direction will slip the cam disk and allow it 50 to remain stationary. Therefore although the ratchet 24 by its contact with the fixed stop 25 first on one side and then on the other due to the reciprocative travel of the platen carriage, is merely oscillated, the inner cam disk 26 is rotated step by step 55 in a closed circular path in one direction only.

Eccentrically mounted in the cam disk 26 is a stud 29, over which is slotted one end of 60 a lever 30 pivoted on the bracket 23 at 31, and having its other end slotted upon a stud 32 carried by the outermost crank-bar 17 of the first container 12, Figs. 15 and 13. When the ratchet 24 reaches and contacts 65 with one side of the fixed stop 25 it will be

partially turned, and in this direction it will pick up and turn the cam disk 26, and said disk, by means of its eccentric stud 29, will swing the lever 30; and said lever, by reason of its engagement with the stud 32, will 70 linearly shift the crank bar 17, which, as heretofore described, will effect the lengthwise shifting of the container and the exposed section of the carbon paper. This operation takes place on the return of the 75 platen carriage; but on the forward stroke the ratchet 24 though engaged by the fixed stop 25 and thereby turned back will slip the cam disk 26, and not turn it; whence it follows that the container is not affected. 80 On the next return travel of the platen carriage the container will again be linearly shifted and ultimately, due to the closed path on the eccentric cam-disk stud 29 the carbon paper section will be linearly shifted 85 step by step in one direction and then step by step back again. It will thus be seen that by this lengthwise adjustment in conjunction with the crosswise adjustment, the manifolding section will present substantial- 90 ly its entire surface during its useful life.

I claim:

1. A manifolding attachment for typewriters, comprising a main paper guide apron adapted to direct a record sheet to and about the platen of the machine to present it in the line of type impact; a manifolding member; and a container adapted to house said manifolding member and present a section thereof in functional position in the line of type impact, said container lying in spaced relation to the main guide apron and forming a second guide apron for a second record sheet, with the exposed section of the manifolding member lying 100 between the two record sheets, and said container being movably mounted to adapt it to vary the exposed section of its manifolding member, with relation to the line of type impact, while said section is in functional position. 105

2. A manifolding attachment for typewriters, comprising a main paper guide apron adapted to direct a record sheet to and about the platen of the machine to present it in the line of type impact; a manifolding member; and a container adapted to house said manifolding member and present a section thereof in functional position in the line of type impact, said container lying in spaced relation to the main guide apron and forming a second guide apron for a second record sheet, with the exposed section of the manifolding member lying 115 between the two record sheets, and said container being movably mounted to adapt it to reciprocatively vary the exposed section of its manifolding member crosswise with relation to the line of type impact, 120 while said section is in functional position. 125

3. A manifolding attachment for typewriters, comprising a main paper guide apron adapted to direct a record sheet to and about the platen of the machine to present it in the line of type impact; a manifolding member; and a container adapted to house said manifolding member and present a section thereof in functional position in the line of type impact, said container lying in spaced relation to the main guide apron and forming a second guide apron for a second record sheet, with the exposed section of the manifolding member lying between the two record sheets, and said container being movably mounted to adapt it to reciprocatively vary the exposed section of its manifolding member lengthwise with relation to the line of type impact, while said section is in functional position.
4. A manifolding attachment for typewriters, comprising a main paper guide apron adapted to direct a record sheet to and about the platen of the machine to present it in the line of type impact; a manifolding member; and a container adapted to house said manifolding member and present a section thereof in functional position in the line of type impact, said container lying in spaced relation to the main guide apron and forming a second guide apron for a second record sheet, with the exposed section of the manifolding member lying between the two record sheets, and said container being movably mounted to adapt it to reciprocatively vary the exposed section of its manifolding member both crosswise and lengthwise with relation to the line of type impact.
5. A manifolding attachment for typewriters comprising a main paper guide apron adapted to direct a record sheet to and about the platen of the machine, to present it in the line of type impact; a manifolding member; a movably mounted container adapted to house said manifolding member and present a section thereof in functional position in the line of type impact, said container lying in spaced relation to the main guide apron and forming a second guide apron for a second record sheet, with the exposed section of the manifolding member lying between the two record sheets, and means for moving said container to adapt it to carry said section of its manifolding member to functional position in the line of type impact and to withdraw it wholly therefrom.
6. A manifolding attachment for typewriters comprising a main paper guide apron adapted to direct a record sheet to and about the platen of the machine, to present it in the line of type impact; a manifolding member; a movably mounted container adapted to house said manifolding member and present a section thereof in functional position in the line of type impact, said container lying in spaced relation to the main guide apron and forming a second guide apron for a second record sheet, with the exposed section of the manifolding member lying between the two record sheets; means for moving said container to adapt it to carry said section of its manifolding member to functional position in the line of type impact and to withdraw it wholly therefrom; and other means for moving said container to vary the exposed section of the manifolding member with relation to the line of type impact while said section is in functional position.
7. A manifolding attachment for typewriters comprising a main paper guide apron adapted to direct a record sheet to and about the platen of the machine, to present it in the line of type impact; a manifolding member; a movably mounted container adapted to house said manifolding member and present a section thereof in functional position in the line of type impact, said container lying in spaced relation to the main guide apron and forming a second guide apron for a second record sheet, with the exposed section of the manifolding member lying between the two record sheets; means for moving said container to adapt it to carry said section of its manifolding member to functional position in the line of type impact and to withdraw it wholly therefrom; and other means for moving said container to vary the exposed section of the manifolding member with relation to the line of type impact while said section is in functional position.
8. A manifolding attachment for typewriters comprising a main paper guide apron adapted to direct a record sheet to and about the platen of the machine, to present it in the line of type impact; a manifolding member; a movably mounted container adapted to house said manifolding member and present a section thereof in functional position in the line of type impact, said container lying in spaced relation to the main guide apron and forming a second guide apron for a second record sheet, with the exposed section of the manifolding member lying between the two record sheets; means for moving said container to adapt it to carry said section of its manifolding member to functional position in the line of type impact and to withdraw it wholly therefrom; and other means for moving said container to reciprocatively vary the exposed section of the manifolding member crosswise with relation to the line of type impact, while said section is in functional position.
9. A manifolding attachment for typewriters comprising a main paper guide

- 8
- apron adapted to direct a record sheet to and about the platen of the machine, to present it in the line of type impact; a manifolding member; a movably mounted container adapted to house said manifolding member and present a section thereof in functional position in the line of type impact, said container lying in spaced relation to the main guide apron and forming a second guide apron for a second record sheet, with the exposed section of the manifolding member lying between the two record sheets; means for moving said container to adapt it to carry said section of the manifolding member to functional position in the line of type impact and to withdraw it wholly therefrom; and means for moving said container to reciprocatively vary the exposed section of the manifolding member both crosswise and lengthwise with relation to the line of type impact, while said section is in functional position.
10. A manifolding attachment for typewriters comprising a main paper-guide apron adapted to direct a record sheet to and about the platen of the machine to present it in the line of type impact; a sheath member lying in spaced relation to the guide apron; a manifolding member; a container 25 slidably fitted and guided in the sheath member and adapted to house the manifolding member and present a section thereof in functional position in the line of type impact, said sheath member and container conjointly forming a second guide apron for a second record sheet with the exposed section of the manifolding member lying between the two record sheets; and means for moving said container in the sheath member to vary the exposed section of the manifolding member with relation to the line of type impact, while said section is in functioning position.
11. A manifolding attachment for typewriters comprising a main paper-guide apron adapted to direct a record sheet to and about the platen of the machine to present it in the line of type impact; a sheath member lying in spaced relation to the guide apron; a manifolding member; a container 50 slidably fitted and guided in the sheath member and adapted to house the manifolding member and present a section thereof in functional position in the line of type impact, said sheath member and container conjointly forming a second guide apron for a second record sheet with the exposed section of the manifolding member lying between the two record sheets; and means for moving said container in the sheath member to reciprocatively vary the exposed section of the manifolding member crosswise with relation to the line of type impact, while said section is in functional position.
12. A manifolding attachment for typewriters comprising a main paper-guide
- writers comprising a main paper-guide apron adapted to direct a record sheet to and about the platen of the machine to present it in the line of type impact; a sheath member lying in spaced relation to the guide apron; a manifolding member; a container 70 slidably fitted and guided in the sheath member and adapted to house the manifolding member and present a section thereof in functional position in the line of type impact, said sheath member and container conjointly forming a second guide apron for a second record sheet with the exposed section of the manifolding member lying between the two record sheets; and means for moving said container in the sheath member to reciprocatively vary the exposed section of the manifolding member lengthwise with relation to the line of type impact, while said section is in functional position.
13. A manifolding attachment for typewriters comprising a main paper-guide apron adapted to direct a record sheet to and about the platen of the machine to present it in the line of type impact; a sheath member lying in spaced relation to the guide apron; a manifolding member; a container 80 slidably fitted and guided in the sheath member and adapted to house the manifolding member and present a section thereof in functional position in the line of type impact, said sheath member and container conjointly forming a second guide apron for a second record sheet with the exposed section of the manifolding member lying between the two record sheets; and means for moving said container in the sheath member to reciprocatively vary the exposed section of the manifolding member lengthwise with relation to the line of type impact, while said section is in functional position.
14. A manifolding attachment for typewriters comprising a main paper-guide apron adapted to direct a record sheet to and about the platen of the machine to present it in the line of type impact; a sheath member lying in spaced relation to the guide apron; a manifolding member; a container 95 slidably fitted and guided in the sheath member and adapted to house the manifolding member and present a section thereof in functional position in the line of type impact, said sheath member and container conjointly forming a second guide apron for a second record sheet with the exposed section of the manifolding member lying between the two record sheets, and means for moving said container in the sheath member to reciprocatively vary the exposed section of the manifolding member both crosswise and lengthwise with relation to the line of type impact, while said section is in functional position.
15. A manifolding attachment for typewriters comprising a main paper-guide

- apron adapted to direct a record sheet to and about the platen of the machine to present it in the line of type impact; a sheath member lying in spaced relation to the guide 5 apron; a manifolding member; a container slidably fitted and guided in said sheath member and adapted to house the manifolding member and present a section thereof in functional position in the line of type impact, said sheath member and container 10 jointly forming a second guide apron for a second record sheet with the exposed section of the manifolding member lying between the two record sheets; means for moving said container forward and back in the sheath member to carry the exposed section of the manifolding member into and out of functional position in the line of type impact and means for supplementally moving 15 said container in the sheath member to vary the exposed section of the manifolding member with relation to the line of type impact while said section is in functional position.
16. A manifolding attachment for typewriters comprising a main paper-guide apron adapted to direct a record sheet to and about the platen of the machine to present it in the line of type impact; a sheath member lying in spaced relation to the guide 20 apron; a manifolding member; a container slidably fitted and guided in said sheath member and adapted to house the manifolding member and present a section thereof in functional position in the line of type impact, said sheath member and container 25 jointly forming a second guide apron for a second record sheet with the exposed section of the manifolding member lying between the two record sheets; means for moving said container forward and back in the sheath member to carry the exposed section of the manifolding member into and out of functional position in the line of type impact and means for supplementally moving 30 said container in the sheath member to reciprocatively vary the exposed section of the manifolding member both crosswise and lengthwise with relation to the line of type impact while said section is in functional position.
17. A manifolding attachment for typewriters comprising a main paper-guide apron adapted to direct a record sheet to and about the platen of the machine to present it in the line of type impact; a sheath member lying in spaced relation to the guide 35 apron; a manifolding member; a container slidably fitted and guided in said sheath member and adapted to house the manifolding member and present a section thereof in functional position in the line of type impact, said sheath member and container 40 jointly forming a second guide apron for a second record sheet with the exposed section of the manifolding member lying between the two record sheets; means for moving said container forward and back in the sheath member to carry the exposed section of the manifolding member into and out of functional position in the line of type impact and means for supplementally moving 45 said container in the sheath member to reciprocatively vary the exposed section of the manifolding member crosswise with relation to the line of type impact while said section is in functional position.
18. A manifolding attachment for typewriters comprising a main paper-guide apron for directing a record sheet to the line of type impact; a manifolding member; a movable container adapted to house said manifolding member and present a section thereof in functional position in the line of type impact, said container lying in spaced relation to the main guide apron and forming a second guide apron for a second record sheet, with the exposed section of the manifolding member lying between the two record sheets; an operating member connected with said container to move it; and means for actuating said operating member to move the container to vary the exposed section of the manifolding member with relation to the line of type impact while said section is in functional position.
19. A manifolding attachment for typewriters comprising a main paper guide apron for directing a record sheet to the line of type impact; a manifolding member; a movable container adapted to house said manifolding member and present a section thereof in functional position in the line of type impact, said container lying in spaced relation to the main guide apron and forming a second guide apron for a second record sheet, with the exposed section of the manifolding member lying between the two record sheets; an operating member connected with said container to move it; and means for actuating said operating member to move the container to vary the exposed section of the manifolding member with relation to the line of type impact while said section is in functional position.
20. A manifolding attachment for typewriters comprising a main paper guide apron for directing a record sheet to the line of type impact; a manifolding member; a movable container adapted to house said manifolding member and present a section thereof in functional position in the line of type impact, said container lying in spaced relation to the main guide apron and forming a sec-

ond guide apron for a second record sheet, with the exposed section of the manifolding member lying between the two record sheets; levers connected with said container to move

it to carry the exposed section of its manifolding member into and out of functional position; a crank bar connected with said container; and means for actuating said crank bar to supplementally move the container to vary the exposed section of the manifolding member with relation to the line of type impact while said section is in functional position.

21. A manifolding attachment for typewriters comprising a main paper guide apron mounted on the platen carriage of the machine for directing a record sheet to the line of type impact; a manifolding member; a container mounted movably upon the platen carriage and adapted to house said manifolding member and present a section thereof in functional position in the line of type impact, said container lying in spaced relation to the main guide apron and forming a second guide apron for a second record sheet with the exposed section of the manifolding member lying between the two record sheets; an operating member connected with said container to move it to vary the exposed section of the manifolding member with relation to the line of type impact while said section is in functional position; and means located on the fixed frame of the machine for actuating said operating member upon the travel of the platen carriage.

22. A manifolding attachment for typewriters comprising a main paper guide apron mounted on the platen carriage of the machine for directing a record sheet to the line of type impact; a manifolding member; a container mounted movably upon the platen carriage and adapted to house said manifolding member and present a section thereof in functional position in the line of type impact, said container lying in spaced relation to the main guide apron and forming a second guide apron for a second record sheet with the exposed section of the manifolding member lying between the two record sheets; a crank bar carried by said container; and means on the fixed frame of the machine coacting with the crank bar upon the travel of the platen carriage to reciprocate the container in order to vary the relation of the

exposed section of the manifolding member ⁵⁵ crosswise with relation to the line of type impact while said section is in functional position.

23. A manifolding attachment for typewriters comprising a main paper guide apron mounted on the platen carriage of the machine for directing a record sheet to the line of type impact; a manifolding member; a container mounted movably upon the platen carriage and adapted to house said manifolding member and present a section thereof in functional position in the line of type impact, said container lying in spaced relation to the main guide apron and forming a second guide apron for a second record sheet ⁷⁰ with the exposed section of the manifolding member lying between the two record sheets; a crank bar carried by said container; and means on the fixed frame of the machine coacting with the crank bar upon the travel ⁷⁵ of the platen carriage to reciprocate the container in order to vary the relation of the exposed section of the manifolding member lengthwise with relation to the line of type impact while said section is in functional ⁸⁰ position.

24. A manifolding attachment for typewriters comprising a main paper guide apron mounted on the platen carriage of the machine for directing a record sheet to the line of type impact; a manifolding member; a container mounted movably upon the platen carriage and adapted to house said manifolding member and present a section thereof in functional position in the line of type ⁸⁵ impact, said container lying in spaced relation to the main guide apron and forming a second guide apron for a second record sheet with the exposed section of the manifolding member lying between the two record sheets; a crank bar carried by said container; and means on the fixed frame of the machine coacting with the crank bar upon the travel of the platen carriage to reciprocate the container in order to vary the relation of the exposed section of the manifolding member both crosswise and lengthwise ⁹⁰ with relation to the line of type impact while said section is in functional position.

In testimony whereof I have signed my ¹⁰⁵ name to this specification.

MALCOLM L. COSSITT.
